Term of patent 14 years

Int. Cl. D7—01

U.S. Cl. D36—8

The figure is an elevational view of a sherbet glass or similar article, showing my new design, it being understood that the glass is circular in plan view, and it being further understood that the bands of cut ornamentation continue about the entire periphery in the paths indicated.

This application is a division of pending United States design patent application Ser. No. 11,705 filed Apr. 30, 1968.

I claim:

The ornamental design for a sherbet glass or similar article, substantially as shown and described.
